US00D928816S

(12) **United States Design Patent** (10) **Patent No.:** **US D928,816 S**
(45) **Date of Patent:** **** Aug. 24, 2021**

(54) **DISPLAY SCREEN OR PORTION THEREOF WITH GRAPHICAL USER INTERFACE**

(71) Applicant: **Lutron Technology Company LLC**,
Coopersburg, PA (US)

(72) Inventors: **Rhythm Agarwal**, Bethlehem, PA (US);
Benjamin F. Bard, Zionsville, PA (US);
Erica L. Clymer, Northampton, PA (US); **Shenchi Tian**, Easton, PA (US)

(73) Assignee: **Lutron Technology Company LLC**,
Coopersburg, PA (US)

(**) Term: **15 Years**

(21) Appl. No.: **29/697,909**

(22) Filed: **Jul. 12, 2019**

Related U.S. Application Data

(63) Continuation of application No. 29/612,918, filed on Aug. 4, 2017, now Pat. No. Des. 854,036.

(51) **LOC (13) Cl.** **14-04**

(52) **U.S. Cl.**

USPC **D14/486**; D14/488

(57) **CLAIM**

The ornamental design for a display screen or portion thereof with graphical user interface, as shown and described.

DESCRIPTION

The sole FIGURE shows a display screen or portion thereof with graphical user interface showing our new design.

The peripheral dashed broken lines illustrate a display screen or portion thereof, and form no part of the claimed design.

Shading represents tonal contrast.
